UNITED STATES PATENT OFFICE.

CHARLES DIMMOCK, OF TORONTO, ONTARIO, CANADA.

COIN-CONTROLLED APPARATUS.

1,353,223.

Specification of Letters Patent. Patented Sept. 21, 1920.

Application filed April 26, 1919. Serial No. 292,989.

To all whom it may concern:

Be it known that I, CHARLES DIMMOCK, a subject of the King of Great Britain, and resident of the city of Toronto, county of 5 York, Province of Ontario, in the Dominion of Canada, have invented certain new and useful Improvements in Coin-Controlled Machines, as described in the following specification and illustrated in the accompanying drawings, that form part of the 10 same.

The principal object of this invention is to devise a simple and effective means of 15 signaling the operation of a coin controlled machine, and the principal feature of the invention consists in the novel arrangement of a striker member in relation to a sounding device and a coin controlled rotatable member, whereby the striking device is 20 operated to strike the sounding member.

In the drawings, Figure 1 is a front elevational view of the interior mechanism of a coin operated signal showing a triple coin arrangement.

25 Fig. 2 is a side elevational view of one of the coin controlled signals.

Fig. 3 is a detail elevational view of the operating member for operating a single stroke signal.

30 Fig. 4 is an elevational detail view of the signal operating device for a two stroke signal.

Fig. 5 is an elevational detail view showing an operating device for a three stroke signal.

It is extremely desirable that a simple 35 form of signaling device for use with pay telephones and other similar devices be produced, as it is well known that those at present in use are continually getting out of order rendering the telephone or other apparatus to be used, inoperative.

According to the present invention the 40 coins are dropped into a slotted chute 1 which is adapted to eliminate any spurious coins and carries the proper coin to a chute 2 which directs it into a pocket 3 arranged upon a rotatable member 4.

The rotatable member is preferably in the 45 form of a disk having the pocket member 3 formed of a V shape and projecting from the face of the disk 4. Several of these pockets are adapted to be brought into register with the discharge end 5 of the chute 2 so 50 that the coin drops into the V-shaped pocket. The bottom of the pocket is formed with a

notch 6 and upon the spindle 7 which forms the support for the rotatable disk 4 is arranged a radial arm 8 which is here shown in the form of a length of wire wrapped 60 around the spindle and secured thereto. The other end of the wire extends radially outward clear of the pockets and carries a counter-balance weight 9.

The spindle 7 extends beyond the casing 65 and is provided with a suitable handle 10.

When a coin is dropped into a chute it is directed into one of the V-shaped pockets and upon the rotation of the handle 10 and spindle 7 the arm 8 engages the coin and 70 rotates the disk. The rotation of the disk member is for the purpose of actuating a signal and this is accomplished in a very simple manner by the arrangement of a hammer 75 in the form of a spring 11, which is here shown secured to the bottom of the machine having its free end arranged to engage one edge of each of the pockets as the disk is rotated. The opposite side of the pocket is preferably formed with a notch 12. A suitable sounding device, such as a bell 13 is arranged adjacent to the spring hammer 11.

When a coin is dropped into a pocket and the arm 8 is operated to rotate the disk the edge of the pocket adjacent to the hammer 85 engages said hammer and springs it back and passing over the end releases it so as to strike the bell. A very simple and effective means of operating a signal is thus produced.

When it is desired to produce a double signal both edges of the pockets are arranged to engage the spring hammer so that with one movement of the disk, the hammer is operated by both edges of the pocket to produce a double signal. This feature is illustrated 90 clearly in Fig. 4.

When a triple sounding of a signal is required a cross pin 14 is arranged intermediate of the width of the pocket. This will not interfere with the depositing of a coin, 100 but the pin engages the spring hammer as the disk is rotated and with the two sides of the pocket produces a triple operation of the hammer and therefore a triple signal.

The structure is extremely simple and may 105 be manufactured at very low cost and there is nothing to get out of order.

What I claim as my invention is:—

1. In a coin controlled machine, the combination with a coin delivering mechanism, 110 a coin receiving rotatable member having a plurality of projecting fixed contacts, a

sounding member, and a striker member adapted to be engaged by said contacts on the rotation of said rotatable member and to be operated to strike the sounding member.

- 5 2. In a coin controlled machine, the combination with a coin delivering mechanism, and a coin receiving rotatable member having a plurality of coin pockets, of a sounding member, a striker member spring engaging the edges of said coin pockets upon the rotation of said member and adapted to strike the sounding member upon clearing said edges.

- 10 3. In a coin controlled machine, the combination with a coin delivering mechanism, and a coin receiving rotatable member having a plurality of V-shaped coin pockets adapted to receive the coins, means adapted

to engage the coins in said pockets, to effect the rotation of said rotatable member, a 20 sounding member, a spring arm adapted to engage the edges of said pockets in rotation and upon disengaging to strike the sounding member.

- 25 4. In a coin controlled machine, the combination with a coin delivering mechanism and a coin receiving rotatable member having a plurality of coin pockets each of said pockets having a fixed number of contact members, a spring arm adapted to be engaged successively by said contact members, and a sounding member adapted to be sounded by said spring arm following the engagement with each of said members.

CHARLES DIMMOCK.
